UNITED STATES PATENT OFFICE.

WILLIAM L. SILVEY, OF LIMA, OHIO.

DYNAMO-ELECTRIC MACHINE.

SPECIFICATION forming part of Letters Patent No. 406,599, dated July 9, 1889.

Application filed April 20, 1888. Renewed April 13, 1889. Serial No. 307,208. (No model.)

To all whom it may concern:

Be it known that I, WILLIAM L. SILVEY, a resident of Lima, in the county of Allen and State of Ohio, have invented certain new and useful Improvements in Armatures for Dynamo-Electric Machines, of which the following is my specification.

My invention relates to an improved construction of the armatures of dynamo-electric machines; and it is the object in my present invention to construct an armature that will be at once simple, cheap, durable, and very strong, without the necessity of complication of parts, as is generally employed by most makers.

Referring to the accompanying cuts, which are made a part hereof, in which similar letters of reference refer to similar parts throughout, Figure 1 is a perspective view of the complete armature without the wires, and Fig. 2 is a side view of the armature-spider B B and shaft A, on which the armature-rings D E are mounted. It will be observed that the armature-blanks E are of very thin sheet-iron, having notches e stamped at regular intervals out of the inside, into which the brass spider B B is pushed. Each of these cut iron blanks is separated from the ones adjacent to it by a paper blank of a corresponding size. Each end of the armature is faced by a heavier iron blank D, an inside view of which is shown in Fig. 3 and outside view in Fig. 4. Fig. 5 is a side view of the stamped sheet-iron blanks. Fig. 6 is a perspective view of the armature disjointed at its center, showing the arms of the spider projecting, with the armature-blanks of each half in place; and Fig. 7 is an upright perspective view of one of the spiders, showing the V-shaped ends of the armature-wings, whose office is to assist in making the armature interlocking. The reason for this heavier plate is in order to have a solid surface for the lugs b to press against in order to keep the lighter blanks together.

The spider B B is divided in its center into two parts, each of which is filled nearly full of the cut blanks and the two pressed together by clamps, at which time it is secured on the shaft by bolts c c. The great peculiarity of this spider is the peculiar construction of the blades. By looking closely at

Fig. 2 it will be observed that each alternate blade is longer than the other, whereas the blade which faces it is short. This continues entirely round the spider. Whenever there is a long blade on one side there is a short one on the opposite half of the spider. When the half-spider is filled with blanks there will be one-half of the wings which do not come flush with the surface, whereas the other half of each alternate wing will project a little above the surface. Where the wings are short on one half of the spider they are long on the other side, and the long wing will press into the notches in the rings where the corresponding short one is, and in this way the two halves are made interlocking, and are as strong as if the spider had been made of one solid piece throughout. This is the particular distinguishing feature of my armature. I sometimes use a V-shaped edge between the ends of the wings, the pointed one being the longer and the smaller one being cut away to correspond. In this case a still stronger joint may be made.

It will be observed by looking at Figs. 3 and 4 that the heavier iron blank D is grooved out on its inner side to make it light and relieve it of material, which will entirely eliminate all danger from heating, which it would do unless this were done.

In case the armature is very large and it is not desirable to use wrought-iron for the two rings at the end of the armature, or where the iron is hard or cast-iron containing a large per cent. of carbon or of too large a bulk, which will cause the iron to heat, I prefer to make these end rings of brass or other non-magnetic material; but I would not alter this form, and would not advise this change of metals, except the trouble from heat is so great as to endanger the insulation.

Having described my invention, what I claim as new, and wish to secure by Letters Patent in the United States, is—

1. An armature for dynamo-electric machines, consisting of two interlocking spiders B B, on which are mounted end plates D, one at each end, with numerous alternate blanks of sheet-iron and paper pressed between them, and the whole mounted on a shaft, substantially as and for the purpose set forth.

2. In an armature for dynamo-electric ma-

chines, the supporting-spiders B B, having each alternate wing shorter than the other, whereby the wings are made to interlock when the armature-blanks D E are mounted thereon, substantially as and for the purpose specified.

3. An armature-spider for supporting a magnetic ring on which the wires are wound,

the spider consisting of separable parts united together by wedge-shaped projections, as set forth and described.

WILLIAM L. SILVEY.
